UNITED STATES PATENT OFFICE

MILTON P. DU PLESSIS, OF EVANSTON, ILLINOIS, ASSIGNOR, BY DIRECT AND MESNE ASSIGNMENTS, TO READY-BILT STORE EQUIPMENT COMPANY, A CORPORATION OF ILLINOIS

STORAGE STRUCTURE

Application filed March 30, 1927. Serial No. 179,451.

- This invention relates to storage structure and has among its objects to provide a relatively inexpensive structure for display and storage purposes which is readily assembled and disassembled without requiring particular skill or effort; to provide such a structure in which the sections may be readily inserted or removed separately regardless of their relative positions in the complete structure; to provide such a structure in which each of the sections or compartments will be supported separately, which will be capable of expansion or reduction to accommodate the desires or needs of the user, and in which the elements will be securely held in assembled relation; to provide a facing strip between adjacent tiers or portions of the complete structure which may be readily attached and removed without the use of tools and without difficulty; to provide such a structure in which the supports for the sections may be adjusted to accommodate different size sections or to provide different size storage or display compartments. Other objects reside in the novel features of construction and arrangement which will be more fully described and disclosed in the following specification and shown in the accompanying drawings in which—
- Fig. 1 is a front elevation of a structure embodying my invention;
- Fig. 2 is a vertical section along the line 2—2 of Fig. 1;
- Fig. 3 is a vertical section along the line 3—3 of Fig. 1, drawn to an enlarged scale to illustrate the method of attachment of the facing strips;
- Fig. 4 is a horizontal section along the line 4—4 of Fig. 2;
- Fig. 5 is a vertical section along the line 5—5 of Fig. 2;
- Fig. 6 is a plan view in detail as viewed from line 6—6 of Fig. 1;
- Fig. 7 is a sectional detail view of a modi-

fication of the section positioning and lifting means.

Like numerals refer to like elements throughout the drawings.

A skeleton structure is assembled or built up by the use of spaced frames, each of said frames comprising a front strip 10, bottom strip 11, rear vertical strip 12 and top cross strip 13, as clearly shown in Figs. 1 and 5.

The front and rear strips 10 and 12 are provided with holes 14 spaced at desired intervals and between these front and rear strips are provided supporting bars 15 shown as of angle-bar construction with the horizontal supporting flanges 15^a. Each of the supporting bars 15 is constructed with a portion of the horizontal flange 15^a at each end outwardly bent or disposed to form a tongue 15^b (see Fig. 4) of a size to closely fit the holes 14. It will be apparent that the bars 15 may be positioned and held by the tongues 15^b in the holes 14 as illustrated in Fig. 2, for example. Additional security is afforded by screws 15^x inserted through angle bars 15 (see Fig. 4). Each of the bars 15 has spaced recesses or apertures 15^c in the horizontal flanges 15^a for a purpose hereinafter described.

Sections of various kinds may be used with the supporting framework described, and in Fig. 1 I have illustrated three of such sections, generally indicated by numeral 20, the upper two having sliding glass doors 20^a. The lower section carries two drawers 20^w. Each of these sections is provided with the bottom 20^b having studs or lugs 20^c projecting from the bottom thereof, as illustrated in Fig. 2. Across the front of the upper sections 20 are provided the bottom strips 20^d and the top strips 20^e between which and within which slide the glass doors 20^a. The sections are constructed for support on the horizontal flanges of supports 15, being slidable into proper position wherein the studs 20^c will seat in the holes or recesses 15^c to provide a species

of yielding lock or engagement to prevent accidental displacement of the sections.

The lower front strips 20^a and bottoms 20^b (except in the case of the lowermost section) 5 depend sufficiently below the bottom 20^b to conceal the supporting bars 15 and to lie adjacent the upper strips 20^c of the subjacent sections. Tops 20^c are provided for the sections 20. At the lower corners of the bottom 10 strips 20^a of each section are provided notches 20^x (see Fig. 1, for example) for the insertion of a screw driver or lever to lift the section to disengage the studs 20^c from the recesses 15^e to permit sliding out of the section. 15

In Fig. 7 I have shown a modification comprising recesses 20^y in the bottoms 20^b of the sections. A small roller 200^c is mounted in each of these recesses and engages recesses 20^x in the supporting bars 15 when fully inserted. With this construction necessity for lifting means or the like is dispensed with as an outward pull upon the sections will cause the rollers to ride up out of recesses 15^e and 25 the sections may be readily rolled out of assembled relation.

A bottom frame comprising the front molding 22, the side strips 22^a and back strip 23 is inserted between each pair of main frame 30 members and secured thereto by bolts 22^a.

Top frames composed of cornice portions 25 and strips 26 and 27 are constructed to lie between the spaced top strips 13 of the main frame and transverse plates or straps 28 are 35 carried by the top frames 13, the straps projecting a short distance at either side of the frame strips 13 (see Fig. 2). The side strips 27 of the top frames are notched to rest upon the straps 28. A panel 29 rests loosely upon 40 or may be secured to the top frames, as illustrated in Figs. 2 and 5. The side bars or strips 27 of the top frames are provided with slots 27^a near the front and rear thereof. Bolts 30 extend through the frame members 13 and 45 the slots 27^a in side strips 27. One of these bolts is extended through the rear of these members and the other through the slot 27^a as illustrated in Figs. 2 and 5. A wing nut 30^a is threaded on one end of each bolt 50 30, and may be tightened in obvious manner to securely tie the top frames together and to the main frame members 13, washers 30^b being provided in well-known manner. The slots 27^a permit partial rotation or tilting of the 55 top frames about the bolts 30, particularly at the front, to permit the bottom of the cornice 25, which is notched at 25^a partially overlying the upper strips 20^c of the upper section, to clear such section and permit its free insertion 60 or removal.

To conceal the joint between adjacent tiers or sections and to cover the main frames from observation, facing strips generally indicated by numeral 35 are provided, having the laterally extending front flanges 35^a and the rear-

wardly extending tail portion 35^b, the latter being of substantially the same width as the frame strips 13, as illustrated in Fig. 4, for example. At the top the facing strips are thickened or constructed to conform to the section of the cornices 25 so as to present a smooth, unbroken top portion at the front of the completed structure. Carried by the tail portions 35^b of these facing strips are the spherical fastening members 36 which may be inserted in the spring sockets 37 carried by the frame members 10 in recesses 10^x, as illustrated in Fig. 3. This construction permits ready attachment and detachment of the facing strips 35, the members 36 and 37 providing a yielding engagement or lock between the facing strips and the frame members, as will be obvious. 70 75 80

In Fig. 6, I have illustrated a means for tying the cornices 25 and the facing strips together detachably although it is not necessary to utilize this feature. As illustrated, the cornices 25 are slotted at 25^b, and a corresponding slot 35^c is provided in the top of the facing strip 35. Slots 25^b open into the enlarged recesses or apertures 25^c. A bolt 40 may be slipped into the slot as illustrated, the head 40^a fitting in one aperture 25^c and a nut 40^b carried on the end of the bolt 40 is inserted in the other aperture 25^c. A 90 small wrench or other tool may be inserted to engage the end 40^b to tie the members together in obvious manner.

In Fig. 1 I have illustrated a partially completed structure in which two large sections 20 are provided, with a smaller section 100 at the bottom.

In the assembly of the structure main frames comprising strips 10, 11, 12 and 13 are assembled and positioned with the attached angle supporting bars 15. The top and bottom members may then be secured to properly spaced frame members and locked thereto, after which such sections as are desired are inserted on the supporting bars, the top frames being tilted or partially rotated to permit insertion of the uppermost section, after which the facing strips 35 are quickly snapped into place. Should it be desired to remove or replace any of the sections after 110 assembly of the completed structure, it is merely necessary to pull off the facing strips 35, insert a screw driver or lever in proper recesses 20^x of the section lying above that which is to be removed, which section and those above it, including the top, are then raised sufficiently to clear the section below, which may then be easily slid out of place, being lifted enough to enable the studs 20^c to clear their recesses 15^e. When the uppermost section is removed it is only necessary to tilt the top frame as described above and lift such section to clear its studs 20^c. 115 120 125

Should it be desired to change the sections which are inserted the supporting bars 15 130

may be adjusted to proper position to accommodate such new sections, which are then readily inserted.

It will be obvious that my structure is susceptible of modification and improvement, and I do not wish to be restricted to the form shown, except as defined in the appended claims.

What I claim is:

- 10 1. A structure of the class described comprising spaced frames, supports carried by said frames, top cross members extending between and secured to said frames, sections independently supported between the frames 15 upon said supporting members, said cross members being constructed to partially overhang subjacent sections and means securing said cross members to said frame members for limited vertical movement.
- 20 2. A structure of the class described comprising spaced frames, supports carried by said frames, top cross members extending between and secured to said frames, sections independently supported between the frames 25 upon said supports, said sections being provided with portions overhanging said supports, said top cross members being constructed to partially overhang the uppermost section of each tier, and means securing 30 said top section to said frames for limited vertical movement to clear said uppermost section.
- 35 3. In combination, parallel frame members spaced each from its adjacent neighbors a distance corresponding to the width of a section to be inserted therebetween, cross members extending between and detachably secured to said frame members, facing strips removably secured to said frame members at 40 the front thereof, supporting members extending from front to back of said frame members, sections independently supported upon said supporting members between said frame members and slidably movable to and 45 from supported position after removal of said facing strips.
- 40 4. In combination, a plurality of vertical tiers of sections, a single frame member between each pair of tiers, supporting members carried by said frame members to separately support each section of said tiers, facing strips attachable to said frame members, said facing strips being provided with relatively wide front portions to partially overlap the sections carried by said supports and being narrowed to extend between said tiers of sections 55 at the rear of said front portion.
- 50 5. In combination, a plurality of vertical tiers of sections, a single frame member between each pair of tiers, supporting members carried by said frame members to separately support each section of said tiers, facing strips attachable to said frame members, said facing strips being provided with relatively wide front portions to partially overlap the sections carried by said supports and being narrowed to extend between said tiers of sections 60 at the rear of said front portion.
- 55 6. In a structure of the class described, spaced frame members, top frames located therebetween, securing members carried by said frame members and engaging and securing said top frames thereto, said top frames being slotted for engagement with said securing members and to permit relative movement of said top frames with respect to said main frame members. 70
7. In a structure of the class described, spaced frame members, top frames extending therebetween, supporting members carried by said spaced frames, sections arranged in vertical tiers and supported on said supporting members, bolts carried by said frame members and extending through said top frames, said top frames being provided with a portion overhanging the uppermost of said sections when in assembled relation and being slotted for accommodation of said bolts and to permit movement of said top frames with respect to said frame members to clear said uppermost sections. 80
8. In combination, spaced framed members, supports carried thereby, sections inserted between said frame members upon said supports, top frames extending between said frame members each being provided with a front portion, each of said front portions partially overlapping the subjacent section, said sections being each provided with a depending front portion at the bottom thereof of overhanging said supports and lying adjacent the upper edge of the subjacent section. 90
9. A knockdown merchandising case comprising spaced separately formed unit rectangular frames comprising outer frames and an intermediate frame, supporting members detachably carried by said frames at 100 the inner sides of said outer frames and at both sides of said intermediate frame, means extending between said frames and removably secured thereto to maintain the same in properly spaced relation after assembly, 105 and sections arranged in vertical tiers between said outer and intermediate frames, said sections being separately supported upon said supporting members and independently movable into and out of position between said 110 frame members.
10. A knock-down merchandising case comprising spaced separately formed unit rectangular frames comprising outer frames and an intermediate frame, cross members 125 located between and secured to said outer and intermediate frames adjacent the top and bottom thereof, the space between said frames and cross members being unobstructed, supporting members detachably 130

carried by said frames at the inner sides of said outer frames and at both sides of said intermediate frame, and sections arranged in vertical tiers between said frames and separately supported upon said supporting members.

11. A knock-down merchandising case comprising spaced separately formed unit rectangular frames comprising outer frames and an intermediate frame, upper and lower cross members located between and secured to said intermediate and outer frames, the space between said frames and cross members being unobstructed, supporting members detachably carried by said frames, and sections separately supported upon said supporting members between said frames, said sections being arranged in vertical tiers.

12. A device of the character described comprising a plurality of separately formed rectangular frames, a rectangular top cross frame, a rectangular bottom cross frame, said frames and cross members being arranged for assembly where desired with said cross members located between and secured to said frame members to properly space and secure the same, adjustable supporting members carried by said frame members and extending from front to back thereof, and sections arranged for independent support and mounting upon said supporting members between said frame members.

13. A device of the character described comprising a plurality of separately formed rectangular frames, a rectangular top cross frame, a rectangular bottom cross frame, said frames and cross members being arranged for assembly where desired with said cross members located between and secured to said frame members to properly space and secure the same, adjustable supporting members carried by said frame members and extending from front to back thereof and sections independently supported upon said supporting members and slidably horizontally into and out of supported position.

14. A knock-down merchandising case comprising spaced separately formed unit rectangular frames comprising outer frames and an intermediate frame, upper and lower cross members located between and secured to said intermediate and outer frames, supporting members detachably carried by said frames, sections separately supported upon said supporting members between said frames and arranged in vertical tiers, and facing strips mounted between said tiers of sections, said frame members and facing strips being provided with inter-engaging yieldable securing means.

15. A knock-down merchandising case comprising spaced separately formed unit rectangular frames comprising outer frames and an intermediate frame, upper and lower cross members located between and secured

to said intermediate and outer frames, supporting members detachably carried by said frames, sections separately supported upon said supporting members between said frames and arranged in vertical tiers, and means to yieldingly secure said facing strips to said frame members, said means comprising securing members carried by said frame members, and said frame members being recessed to accommodate said securing members.

In testimony whereof, I have signed my name to this specification.

MILTON P. DU PLESSIS.
